(54) **CHARCOAL BURNER, CONICAL ARCH**

(76) Inventor: **Ezra B. Gilbert**

Esra B. Gilbert, Ephrata, Montgomery, New York

Letter Patent

The subscriber refers to in this Letter Patent and making part of the same containing a description in the words of the inventor Esra B. Gilbert himself of his improvement in the Crucical Arch Charcoal Burner.

Be it known that Esra B. Gilbert of the town of Ephrata in the County of Lancaster & State of New York have invented a new and useful improvement in the art of manufacturing Charcoal called "Gilbert Crucical Arch Charcoal Burner" which is described as follows, reference being had to the annexed drawings of the same making part of this specification.

This Crucical Arch Charcoal Burner is to be built of brick or stone and a convenient size, will be about sixteen feet diameter at the base and twelve feet high, although it, as well as its parts may be varied to suit circumstances.

The brick or stone (the former being preferable) is to be laid in lime mortar & cement commencing at the base by a circular wall from six to nine inches in thickness, leaving apertures or vents 6 to four inches square about twenty inches apart all around the wall except certain spaces to be left for doors. These spaces for the doors are to be from three to four feet in width and from six to six feet in height. The doors may be narrower at the top than at the bottom. At the spaces above the apertures or vents first mentioned commences another row of apertures or vents 6. four inches by two and dividing the spaces of the first row. Here the wall is to be raised about two feet four inches contracting the diameter of the circle at the same time about two feet. Here leave another row of vents 6. also about twenty inches apart of four inches by two. Then raise the wall three feet more contracting the diameter of the circle four feet, at which point add another row of vents 6. of the size of those last mentioned and from twenty to twenty four inches apart. Then carry up said wall contracting it in size so as to make the circle one foot in diameter at the height of twelve feet and the airings around the wall over the space last mentioned to be in four vents 6. of the size of those last mentioned. When the

conical arch Charcoal burner is thus constructed, fill it with wood commencing at the bottom with sticks of small size to be placed in layers six inches from the ground and laid up at least one foot high beforeise in a loose manner, then lay in wood in a horizontal manner as compactly as possible to the top of the burner. After the wood is thus put in close the doors, for convenience each door should be made in three pieces or parts of brick and mortar and kept together by bars of iron. Fire must be communicated to the wood through the opening at the top and as soon as the fire burns freely close this opening with bricks to be kept together as the pieces of the doors are; as soon as the fire approaches the upper part which will be discoverable by the bluish colour of the smoke they are to be closed with brick and mortar so as to prevent air and smoke from passing through them; and the fire consumed the other vents are to be closed in like manner except the vents at the side which is to be kept open until the fire is seen through them.

Then close the lower tier of vents as soon as the fire is seen through each one. When all are closed care should be taken that neither smoke nor air escapes from any part of the structure.

The Coal burner is to be kept thus closed four four to five days when the fire will become smothered and extinguished at which time the doors can be taken down and the coal taken out fit for use.

The whole process of burning and cooling the coal taking about seven or eight days. That I claim as my invention and never before known and while I desire to secure by Letters Patent is the above described conical arch Charcoal burner for manufacturing charcoal
